UNITED STATES PATENT OFFICE.

WILLIAM T. FISHER, OF BROAD AXE, PENNSYLVANIA, ASSIGNOR TO SUSAN D. FISHER, OF SAME PLACE.

FASTENER FOR WINDOW-SHUTTERS.

SPECIFICATION forming part of Letters Patent No. 553,499, dated January 21, 1896.

Application filed May 17, 1895. Serial No. 549,651. (No model.)

To all whom it may concern:

Be it known that I, WILLIAM T. FISHER, a citizen of the United States, residing at Broad Axe, in the county of Montgomery and State 5 of Pennsylvania, have invented certain new and useful Improvements in Fasteners for Window-Shutters, of which the following is a specification.

My invention relates to a new and useful 10 improvement in fasteners for window-shutters, and has for its object to provide such a device that shall be simple in construction and automatic in operation, and which will so hold a blind when open as to prevent it 15 from rattling; and with this end in view it consists in the details of construction and combination of elements hereinafter set forth, and then specifically designated by the claims.

In order that those skilled in the art to 20 which this invention appertains may understand how to make and use the same, I will describe its construction and operation in detail, referring by number to the accompanying drawings, forming a part of this specification, and in which—

Figure 1 is a perspective of my device in proper relative position to a shutter when open and in engagement therewith; Fig. 2, a like view showing the shutter disengaged from 30 the fastener, and Fig. 3 a central vertical section of a slightly-modified form of my improvement.

Similar numbers denote like parts in all of the views of the drawings.

35 1 represents a strip of sheet metal, so bent as to form a latch 2 and spring-buffer 3, and it is riveted or otherwise secured to the angle-iron 4, by which the device may be secured to the outer wall of a house, within the field of 40 the shutter 5, when swung open.

6 is a stem, secured at its upper end to the latch 2, and terminating in a button 7, by which said latch may be depressed against its resiliency, so that it will be seen that during 45 the movement of a blind when swung open against the wall its lower edge will come in contact with the upper surface of the latch 2, and, riding thereon, depress said latch until it has passed the inner edge thereof, when 50 the latter will spring up and securely hold the shutter against any reverse movement.

The spring-buffer 3 is so disposed relative to the latch that the shutter will come in contact with and bear thereon before passing the edge of the latch, and the spring action of 55 said buffer will hold the shutter firmly against the latch, thereby preventing any rattling of said shutter.

When it is desired to close the shutter, it is only necessary to depress the latch 2 by 60 manipulation of the button 7, when the spring-buffer 3 will impart to the shutter an initial movement sufficient to clear the latch, which will assist materially in closing the shutter and obviate the necessity of having to use 65 both hands to disengage the shutter from its fastening, as has been the case heretofore.

The metal strip 1, from which the operating parts of my device are formed, may be made of a sufficient width as not to mar the portions of the shutter with which it comes in contact, or, if deemed advisable, I may provide a U-shaped striker-plate 8, adapted to be secured upon the under edge of the shutter, so as to ride over the latch and form bearing-surfaces against which the spring-buffer and 75 latch may bear.

In the modification shown in Fig. 3, 9 represents a rubber cushion, set in a suitable recess in the spring-buffer 3, and this cushion 80 is intended to receive and come in contact with the shutter when swung open to prevent marring its surface when the striker-plate is not used.

Heretofore the rattling of a shutter occasioned by the movements of the air has proved very annoying, and the fastenings in use have failed to overcome this disadvantage, in that no provision was made for confining the shutter against slight movement 90 when held in an open position; but by my improvement I have entirely overcome this annoyance and provided a device which can be produced at small cost, and is readily attached to any building, and by the use of 95 which a shutter may be securely held open or automatically thrown out of engagement with the latch when said latch is depressed.

Having thus fully described my invention, what I claim as new and useful is—

1. In a shutter fastener, the latch 2, stem 6, and button 7, for depressing the same, in

combination with the spring buffer 3, and angle plate 4, by which the device is secured to a wall, as specified.

2. In combination with a shutter, a striker plate 8, latch 2, shank 6, button 7, buffer 3, and angle plate 4, all arranged to operate as and for the purpose specified.

In testimony whereof I have hereunto affixed my signature in the presence of two subscribing witnesses.

WILLIAM T. FISHER.
